(57) **CLAIM**

The ornamental design for an in-vehicle amplifier, as shown and described.

DESCRIPTION

FIG. 1 is a perspective view of an in-vehicle amplifier, showing my design;

FIG. 2 is a top view thereof;

FIG. 3 is a bottom view thereof;

FIG. 4 is a front view thereof;

FIG. 5 is a rear view thereof;

FIG. 6 is a left side view thereof; and,

FIG. 7 is a right side view thereof.

The broken lines in the Figures show portions of the in-vehicle amplifier and forms no part of the claimed design.
